Attorney.

UNITED STATES PATENT OFFICE.

GEORGE EDENSOR DORMAN, OF CHICAGO, ILLINOIS, ASSIGNOR TO THE STANDARD ELECTRIC COMPANY, OF ILLINOIS.

FIELD-MAGNET FOR DYNAMOS.

SPECIFICATION forming part of Letters Patent No. 470,749, dated March 15, 1892.

Application filed December 17, 1890. Serial No. 374,994. (No model.)

To all whom it may concern:

Be it known that I, GEORGE EDENSOR DORMAN, a subject of the Queen of Great Britain, residing at Chicago, in the county of Cook and State of Illinois, have invented a new and useful Improvement in Field-Magnets for Dynamo-Electric Machines, of which the following is a full, clear, and exact specification.

My invention relates to improvements in the field-magnets of dynamo-electric machines, and has for its object to provide certain new and useful features more particularly illustrated in the accompanying drawings, wherein—

15 Figure 1 is an end view of a field-magnet. Fig. 2 is a side view of a portion thereof. Fig. 3 represents a side and end view of a section or segment.

Like parts are indicated by the same letters 20 or numerals in all the figures.

A A are series of segments or sections provided each with the curved body portion and the inwardly-projecting ends B B, radial to the arc of the body of the segment A.

25 C C are bolt-holes through such segments to receive the bolts D D, which are provided with the countersunk heads E E, received into suitable recesses in the circular end portions F of the field-magnets. These end portions

30 are provided with the legs G. The end portion of course must be of the outline of the field-magnet in cross-section, or, as in the present case, must be circular, and in order to construct a field-magnet of the parts herein shown it is only necessary to place alternate sections 35 or segments A upon one of these end pieces F and then to place suitable bolts D D through the appropriate holes C C in such segments. Thus we would lay down first the segments 3

40 3 3 3, which are shown in full lines and are supposed to be next to the end piece F. These sections or segments are indicated in Fig. 1 in full lines. We now place alternate sections 4 4, (shown partly in dotted lines in Fig. 1,) 45 the end portions B B of which are in alignment with the end portions of the segments 3 3. These segments of course also receive the bolts D D, and in like manner successive overlapping sections are built up until the

50 field-magnet has reached the desired length, whereupon the ends of the bolts D D will be

suitably secured to or in a similar end piece to that shown in the drawings. When thus completed, we have a field-magnet of flat successive segments with inwardly-projecting 55 pole-pieces made up each of thin sheets, all in alignment and all radial to the general outline of the field-magnet. Such a field-magnet so formed will be in the form of a cylinder with inwardly-projecting oblong substantially-solid pole-pieces and an exterior cylindrical portion open-worked or slotted, as shown in Fig. 2. The end pieces F F would preferably be of cast-iron, while the segments out of which the field-magnet is constructed would 65 preferably be thin sheets of wrought-iron.

I claim—

1. In a dynamo-electric machine, a series of short overlapping arc-shaped segments with inwardly-projecting ends in alignment, so as 70 to form a circular field-magnet with inwardly-projecting pole-pieces.

2. In a dynamo-electric machine, a series of short overlapping arc-shaped segments with inwardly-projecting ends in alignment, so as 75 to form a circular field-magnet with inwardly-projecting pole-pieces, and transverse bolts passing through such segments and pole-pieces, so as to securely connect the whole together. 80

3. In a dynamo-electric machine, a field-magnet consisting of a series of curved segments with inwardly-projecting ends in alignment with each other, so as to form inwardly-projecting pole-pieces for carrying the field- 85 magnet coils, and transverse bolts passing through such segments and pole-pieces, so as to securely connect the whole together.

4. In a dynamo-electric machine, a field-magnet consisting of a series of segments alternately overlapping at the ends and provided with inwardly-projecting ends placed in alignment, so as to form inwardly-projecting pole-pieces, such segments secured together by bolts which pass through them, so 90 as to form an open-work or slotted supporting portion with inwardly-projecting substantially-solid pole-pieces. 95

GEORGE EDENSOR DORMAN.
